UNITED STATES PATENT OFFICE.

EMILE COSTE, OF NEW YORK, N. Y., ASSIGNOR TO TITUS BLATTER & COMPANY, OF NEW YORK, N. Y., A CORPORATION OF NEW YORK.

DESIGN FOR AN ARTICLE OF MANUFACTURE.

52,523.

Specification for Design.

Patented Oct. 8, 1918.

Application filed July 17, 1918. Serial No. 245,422. Term of patent 3½ years.

To all whom it may concern:

Be it known that I, EMILE COSTE, a citizen of the Republic of France, residing at New York, in the county of New York and State of New York, have invented a new, original, and ornamental Design for an Article of Manufacture, of which the following is a specification, reference being had to the accompanying drawing forming part thereof, in which,—

The figure is a plan view of a piece of textile fabric illustrating my new design.

It is to be understood, however, that my present new and ornamental design is applicable not alone to fabrics, but to carpets, wall paper and similar articles of manufacture having surface ornamentation without in the least departing from my invention.

I claim as of my invention:

The ornamental design for an article of manufacture substantially as shown.

In testimony whereof I affix my signature in the presence of two subscribing witnesses.

EMILE COSTE.
